SHADOW BOX

Joel J. Glassman, Nashville, Tenn.

Application May 18, 1959, Serial No. 55,944

Term of patent 7 years

(Cl. D29—20)

Fig.1

Fig.3

Fig.4

Fig.2

Fig. 1 is a front perspective view a shadow box showing my new design;

Fig. 2 is a rear perspective view thereof;

Fig. 3 is a side elevational view thereof; and

Fig. 4 is a top plan view thereof.

The dotted line showing in Fig. 1 is for convenience of illustration.

I claim:

The ornamental design for a shadow box, as shown and described.
